DEFLECTOR

Harry A. Reichman, Chicago, Ill.

Application April 23, 1954, Serial No. 30,155

Term of patent 3½ years

(Cl. D14—6)

To all whom it may concern:

Be it known that I, Harry A. Reichman, residing in the city of Chicago, county of Cook and State of Illinois, have invented the new, original, and ornamental Design for Deflector, of which the following is a specification, reference being had to the accompanying drawing, which forms a part hereof.

Fig. 1 is a miniature perspective view of a deflector embodying my new design.

Fig. 2 is a front elevational view thereof.

Fig. 3 is a sectional view taken approximately on line 3—3 of Fig. 2 on an enlarged scale, and

Fig. 4 is a sectional view taken approximately on line 4—4 of Fig. 2 on an enlarged scale.

The dotted line disclosure of an automobile window ventilator in Fig. 1 is shown only for the purpose of illustration.

I claim:

The ornamental design for a deflector, as illustrated and described.
